UNITED STATES PATENT OFFICE

MAXWELL M. UPSON, OF ENGLEWOOD, NEW JERSEY, ASSIGNOR TO RAYMOND CONCRETE PILE COMPANY, OF NEW YORK, N. Y., A CORPORATION OF NEW JERSEY

COMPOSITE PILE

Application filed August 14, 1926. Serial No. 129,143.

This invention pertains to composite piles formed by first driving a wood or precast concrete pile to constitute the lower portion and then forming thereon a cast-in-place concrete upper portion to complete the pile structure.

In building piles as above great difficulty has always been encountered in preventing the upper or cast-in-place section from lifting off the lower section after the pile is finished, due to the heaving action of the ground, caused largely by the driving of adjacent piles.

To overcome this difficulty, various arrangements of sockets and reinforcing bars have been used to lock the upper and lower sections together.

I propose now to obviate the necessity for such special locking devices, by using the pile shell itself to lock the upper and lower sections together. In its preferred form the shell is formed of corrugated sheet steel and the corrugations are screw-threaded. In general, the arrangement disclosed in the present invention consists in screwing the lower end of the shell of the cast-in-place section onto the upper end of the lower section, either directly or through an intermediate sleeve so that, when the upper section is cast, the two sections will be so firmly locked together by the shell as to prevent their subsequent separation due to heaving of the ground.

This application is in part a continuation of my copending application Serial No. 5,436, filed January 29, 1925.

Further and other objects and advantages will be hereinafter set forth in the accompanying specification and claims, and shown in the drawings, which by way of illustration show what is now considered to be the preferred embodiment of the invention.

Fig. 1 shows an arrangement in which a comparatively short corrugated sleeve is screwed onto the upper end of a wood pile, with the lower end of the upper shell screwed into the sleeve. This figure also shows details of the collapsible core used in driving the pile after the shell is in place.

Fig. 2 is a sectional elevation (with the

upper and lower ends of the composite pile broken away) of one form of composite pile embodying features of my invention.

Figs. 3, 4 and 5 are fragmentary detail sectional elevations showing certain modifications of pile structure variously embodying features of my invention.

Fig. 6 is a substantial copy of Fig. 10 of my application Serial No. 5,436, in which the shell has a portion directly threaded onto the upper end of a precast concrete lower section.

After the lower section of the composite pile has been driven, a pile shell and suitable driving core are assembled on top thereof. The core may be of either the collapsible or non-collapsible type described in my Patent No. 1,491,832, April 29, 1924. A collapsible core is shown in Fig. 1. The lower end of the center rod 10, by which the leaves or plates 12 are expanded and contracted, is provided with an enlarged lower end 14 having a tubular extension 16 which surrounds the tenon 18 of the lower pile section, which may be of wood or concrete. The lower ends of plate 12 extend down around the tenon towards the body of the pile 20. To ease the driving impact on top of the tenon, it is customary to provide a cushion 22 between the tenon and the bottom of rod 10.

In the modification shown in Fig. 1, the upper end of the body 20 of the lower pile section is threaded and a comparatively short corrugated sleeve 24 is screwed onto the pile. The corrugated shell 26 of the upper section is screwed into sleeve 24. It will be readily appreciated that after shell 26 is filled with concrete, the two sections of the pile will be so effectively locked together as to avoid all possibility of separation due to heaving of the ground.

Fig. 6 shows an arrangement in which the upper shell itself is screwed directly onto the lower pile section without any intermediate coupling sleeve 24.

There are difficulties in threading the body of the lower pile. Therefore, modifications have been found desirable to meet conditions of actual practice. Some of these modifications are shown in Figs. 2-5, inclusive. In Fig. 2, a ring 30 of concrete, wood, asphalt,

iron or other material which will stand the impact of driving, is fitted snugly around tenon 18. The outer surface of ring 30 is threaded to receive the corrugated coupling 24, and the upper shell 26 is screwed into 24 as before. A number of boat spikes 32 are driven through ring 30 to prevent the ring rising on tenon 18. This is a very effective construction as it not only prevents separation of the pile sections but also prevents entry of water into the joint. If desired, the shell 26 may be screwed onto ring 30 and coupling 24 omitted.

In Fig. 3, a deep circumferential slot 34 is cut in the top of lower pile body 20, and into slot 34 is fitted the cylindrical lower end 36 of coupling 24. A number of heavy spikes 38 are driven into the pile body through holes 40 in the ring 36. The upper shell 26 is threaded into coupling 24 as before.

In Fig. 4 is shown another variation, in which coupling 24 is provided with a bottom end which is bent inwardly and upwardly around the lower ends of plate 12 to form an inner upturned ring 42. A number of spikes 44 are driven into tenon 18 just above ring 42 so that they prevent ring 42 from rising. This arrangement is self-locking because the spikes are driven first and then the coupling ring is forced down past them, the upper edge of the ring finally springing into place beneath the heads of the spikes and thus effectively preventing the upper section from rising. The tenon may be grooved as at 50, if desired, to accommodate the ring 42.

Still another modification is shown in Fig. 5. This is similar to Fig. 4 except that the inner upwardly extending ring 42 is not so high, and the spikes 44 extend through the outer wall of coupling 24 as well as over the top of inner ring 42. In this arrangement the lower ends of blades 12 must be provided with downwardly opening slots or grooves 46 for the spikes, in order to permit removal of the core after the upper pile section has been driven. Also, the space between the core plates, when expanded, is increased so that the core when collapsed may be lifted out without unscrewing.

It is customary to make coupling sleeve 24 of considerably thicker material than the shell itself.

It is to be understood that the invention is not limited to the specific construction herein illustrated and described but can be embodied in other forms without departure from its spirit.

What I claim is:

1. A composite pile comprising, in combination, a precast lower section, a cast-in-place upper section and a shell in which said upper section is cast, said shell being locked to the upper end of said lower section by screw threads.
2. A composite pile comprising an upper

section enclosed by a shell, a lower section with a tenon on its upper end, a ring fitted around said tenon, means to fasten said ring to said tenon, and a coupling sleeve threaded onto said ring and said shell to lock said ring and said shell together. 70

3. A composite pile comprising, in combination, a lower section, a coupling sleeve secured to the top of said lower section, a shell, an upper section cast in said shell, and means for locking said shell to said coupling sleeve, said locking means comprising screw threads on said shell and said sleeve. 75

4. A composite pile comprising an upper section, a lower section, a member fast to the upper end of said lower section, a shell surrounding said upper section, and means for locking said shell to said member, said locking means comprising screw threads on said member for engaging screw threads on said shell. 80

5. A composite pile comprising an upper section, a lower section, a member fast to the upper end of said lower section, a shell surrounding said upper section, and means for locking said shell to said member, said locking means comprising a coupling sleeve screw threaded to said member and to said shell. 85 20

6. A composite pile comprising in combination, a lower section, a coupling sleeve secured to the top of said lower section, a shell, an upper section cast in said shell, and means for positively locking said shell to said coupling sleeve before the concrete is poured. 95

7. A composite pile comprising an upper section, a lower section, a member fast to the upper end of said lower section, a shell surrounding said upper section, and means for positively locking said shell to said member before the concrete is poured. 100 105

In testimony whereof I hereto affix my signature.

MAXWELL M. UPSON.
